UNITED STATES PATENT OFFICE.

WALTER SCOTT, OF PLAINFIELD, NEW JERSEY.

MEANS FOR COOLING STEREOTYPE-CASTING BOXES.

No. 796,091.

Specification of Letters Patent.

Patented Aug. 1, 1905.

Application filed June 20, 1903. Serial No. 162,358.

To all whom it may concern:

Be it known that I, WALTER SCOTT, a citizen of the United States of America, and a resident of Plainfield, Union county, State of New Jersey, have invented certain new and useful Improvements in Means for Cooling Stereotype-Casting Boxes, of which the following is a specification.

My invention relates generally to stereotype-casting molds, and has more particular reference to means for cooling the casting-surface of the cope.

The object of the invention is to improve the means for cooling the said casting-surface; and the said invention comprises the hereinafter-described features of construction and combination of parts.

In the drawings, Figure 1 is a vertical sectional view of the cope and adjacent parts, showing one form of the invention. Fig. 2 is a transverse sectional view on the line $z-z$ of Fig. 1. Fig. 3 is a vertical sectional view showing a modification.

Similar characters of reference indicate corresponding parts in the different views.

Broadly, my invention contemplates a pre-heating of the cold water before it encounters the casting-surface of the upright stationary cope by leading it through a reservoir located below the casting-surface of the said cope, the walls of the said reservoir transmitting the heat of the casting-surface to the water before the said water enters the upright water-space immediately adjacent to the casting-surface of the cope. This principle is conveniently embodied in the construction shown in Figs. 1 and 2, in which 1 indicates a cope stationarily supported in an upright position and composed of an outer shell 2 and an inner shell 3, suitably fastened together. The outer shell forms an upright casting-surface 3^a, the plate being cast between it and the movable drag 4. The general construction of the casting-mold is preferably similar to the one shown and claimed in an application filed by me on the 3d day of July, 1901, Serial No. 66,975, the said general structure not being claimed in the present application. The inner and outer shells when fastened together form an upright water-space 5 immediately adjacent to the casting-surface of the cope. At the lower end of the cope, below the casting-surface, is a reservoir 6, communicating with the upright water-space. The inlet 7 leads to the said reservoir from any suitable source of supply.

of water. The inner shell is provided with a seat 8, extending into the upright water-space and provided with one or more upright pipes 9, communicating at the upper end with the upright water-space and at the lower end with the outlet 10. The water enters at the inlet and flows into the reservoir, where the extreme chill of the cold water is taken off. It then rises in the upright water-space and descends through the pipes 9 and out through the outlet.

A modification is shown in Fig. 3 in which the upright stationary cope 11 is cored out, so as to form an upright water-space 12 immediately adjacent to the casting-surface 13. In this instance the water enters at the inlet 14, flowing into the reservoir 15, located, as in the other instance, below the casting-surface of the cope, communicating with the water-space 12 and out through the outlet 16 at the upper end of the cope.

In both of these constructions the water upon entering the reservoir becomes sufficiently heated by contacting with the walls of the same so as not to chill the casting-surface, the lower end of which would be particularly exposed, and still enables the water to reach the water-space adjacent to the casting-surface of the cope before it becomes so heated as to be ineffective.

Some features of construction shown in the present application are not claimed herein, but are claimed in a sister application filed on June 20, 1903, Serial No. 162,359.

Having thus described my invention, what I claim is—

1. In a stereotype-casting mold, an upright stationary cope, an upright casting-surface on the said cope, a water-inlet, a water-outlet, an upright water-space immediately adjacent to the said casting-surface, and a water-reservoir in the cope below the said casting-surface whose walls will transmit the heat from the casting-surface to the water so that the latter is preheated before coming in contact with the said casting-surface.

2. In a stereotype-casting mold, the combination with an upright stationary cope, of an upright casting-surface on the said cope, a water-inlet, a water-outlet, an upright water-space immediately adjacent to the casting-surface, and a water-reservoir in the cope below the said casting-surface where the chill of the cold water is taken off previous to entering the upright water-space.

3. In a stereotype-casting mold, the combination with an upright stationary cope having an upright casting-surface, of a water-reservoir located below the casting-surface of the cope, an inlet for the said reservoir, an upright water-space connected with said reservoir immediately adjacent to the said casting-surface, and an outlet from the said water-space at the upper end of the said cope.

4. In a stereotype-casting mold, an upright stationary cope, an upright casting-surface on the said cope, an inclined pouring-gate above the said casting-surface, a water-reservoir located below the casting-surface

of the cope, a water-inlet for the said reservoir, an upright water-space connected with the said reservoir immediately adjacent to the casting-surface, an inclined water-space terminating the said upright water-space at its upper end and immediately adjacent to the inclined pouring-gate, and an outlet connected with the said inclined water-space.

Signed at New York this 11th day of June, 1903.

WALTER SCOTT.
